(57) **CLAIM**

The ornamental design for footbed system for footwear, as shown and described.

DESCRIPTION

FIG. 1 is a top, front and left side perspective view of a footbed system for foot-wear in accordance with the new design showing a top, front and left side perspective view of an insole of the footbed system for footwear which is positioned above a lower wedge member of the footbed system for footwear also shown in a top, front and left side perspective view;

FIG. 2 is a top, front and left side perspective view of the insole and lower wedge member of FIG. 1

FIG. 3 is a top plan view of the insole of FIG. 1;

FIG. 4 is a bottom plan view of the insole of FIG. 1;

FIG. 5 is a left side elevation view of the insole and lower wedge member of FIG. 1;

FIG. 6 is a right side elevation view of the insole and lower wedge member of FIG. 1;

FIG. 7 is a top plan view of the lower wedge member of FIG. 1;

FIG. 8 is a bottom plan view of the lower wedge member of FIG. 1;

FIG. 9 is a left side elevation view of the lower wedge member of FIG. 1;

FIG. 10 is a right side elevation view of the lower wedge member of FIG. 1; and,

FIG. 11 is a cross-sectional view of the insole of FIG. 1.
